UNITED STATES PATENT OFFICE.

ARTHUR D. LOVEREN, OF NEWARK, NEW JERSEY, ASSIGNOR TO AMERICAN AUTOMATIC VENDING MACHINE COMPANY, A CORPORATION OF DELAWARE.

VENDING-MACHINE.

1,149,377.

Specification of Letters Patent. Patented Aug. 10, 1915.

Application filed September 15, 1913. Serial No. 789,767.

To all whom it may concern:

Be it known that I, ARTHUR D. LOVEREN, citizen of the United States, and resident of Newark, in the county of Essex and State 5 of New Jersey, have invented certain new and useful Improvements in Vending-Machines, of which the following is a specification.

This invention relates to vending machines, particularly machines of this character which dispense candy, chewing-gum or other small light articles, such as lead pencils, cigars or the like.

One of the objects of the present invention is to provide a machine of this character which is entirely automatic, the drop of the coin itself setting in motion the mechanism for ejecting the article.

Another object is to provide a mechanism 20 for machine of this character which is certain in its action and will accurately dispense the required article or number of articles without fail every time a coin is dropped in the coin chute.

A further object is to provide a machine 25 of this character which is not readily tampered with and will not respond unless a coin is actually dropped in the chute.

The various further objects and advantages will more fully appear from the detailed description and the features of novelty will be particularly pointed out in the claims.

In the accompanying drawings illustrating 30 the preferred embodiments of my invention, Figure 1 is an elevation, partly in section along line 1—1 of Fig. 2, of one form of vending machine with my invention applied thereto. Fig. 2 is a section taken along line 2—2 of Fig. 1. Fig. 3 is a sectional elevation of the lower portion of the machine, the section being taken along line 3—3 of Fig. 2, at right angles to the section in Fig. 1. Fig. 4 is a section similar to Fig. 40 3 illustrating the mechanism in operation, one ball having dropped upon the feed table previous to its discharge. Fig. 5 is an elevation partly in section of a modified form of apparatus embodying the invention. Fig. 6 is a section taken along line 6—6 of Fig. 5. Fig. 7 is a detail view of the supporting dog for the trip lever. Fig. 8 is a fragmental sectional elevation, and Fig. 9 is a fragmental sectional plan view of a modified form of trip lever. Fig. 10 is a

fragmental sectional elevation of a modified coin chute to be used in connection with the trip lever illustrated in Figs. 8 and 9. Fig. 11 is a sectional elevation partly broken away of a modified form of the invention 60 adapted for vending long cylindrical objects, such as stick candy, pencils and the like. Fig. 12 is a sectional elevation of a further modified form of the invention adapted for dispensing rectangular articles, 65 such as chewing-gum and the like.

Referring to Figs. 1 to 4 of the drawing, the machine is provided with a suitable reservoir 10 containing the balls 11 which are discharged through the mouth 12 of the 70 reservoir by the mechanism operated by the coin. This mechanism consists of a tiltable feed table 13 having an upstanding arm 14

which forms a support for the balls and permits the same to drop upon the table when the latter is tilted. The table is pivoted at a suitable point 15 at or adjacent to the center line of the balls, and when the table is depressed, as in the position illustrated in Fig. 3, the outer end of the arm 14 contacting the bottom of the ball is swung to a position at or slightly passed the center line of the balls. The latter are thus supported and the weight thereof will not tend to disturb the position of the support or 80 table. When the latter is tilted into position indicated in solid lines in Fig. 4, as by the insertion of a coin in the slot as hereinafter explained, one ball drops into the pocket formed by the table and the arm 14, while 90 the succeeding ball is held up by the ball in the pocket. Immediately thereafter the weight of the ball itself, as well as the weight of the table, will swing the latter downward, as illustrated in dotted lines in Fig. 4, and the ball thereon will roll off into a suitable bowl, to which ready access is had by the person depositing the coin, the arm 14 in the meantime swinging 95 rapidly over to support the succeeding ball. A roller 16 may be mounted at the outer end of the arm 14 which contacts the balls so as to facilitate the tilting action of the table, and the top of the table may be formed with a slightly concaved surface 17 100 so as to more readily guide the ball to roll down to the proper place for discharge.

The table is tilted by the action of the coin as follows: Disposed preferably at one side of the reservoir is a coin chute 18 into 110

which a coin may be deposited through the coin slot 19. Projecting under the bottom of the coin chute is the end of a trip lever 20 fulcrumed at a suitable point 21 and 5 formed with an arm 22 engaging the table preferably at the bottom thereof. As the coin drops to the bottom of the chute it hits the projecting end of the lever 20 swinging the same and thereby tilting the table 13 to dispense a ball as previously explained. The coin may then drop in a suitable coin box 23 located at the bottom of the casing. By the use of the trip lever, the mechanism is rendered very sensitive and the transverse 15 mounting of the trip lever relatively to the feed table results in a very compact construction as readily appears from Fig. 2 of the drawing. To prevent tampering with the mechanism by an unauthorized person, 20 a hinged flap 24 is provided adjacent the lower edge of the table 13 and disposed so as to open outward to permit the ball to be discharged, but preventing the insertion of a wire or other instrument through the discharge opening. The rear wall of the coin chute is also formed with a plurality of apertures 25 to prevent the insertion of a wire down the chute through the coin slot. As the latter opens outward horizontally 30 and the chute extends down vertically, a wire inserted through the slot will contact the forward wall of the coin chute and will catch in one of the apertures 25. Any suitable guideway may be provided for the ball 35 when it leaves the table and passes the flap 24. In the form of apparatus illustrated in Figs. 1 to 4, the guideway 26 curves toward the midwidth of machine and opens into the discharge bowl 27 located at the front 40 of the machine.

In the modification illustrated in Figs. 5, 6 and 7, the tilting table 30 is formed with a laterally inturned mouth 31 through which the ball may be discharged into a tube 32 45 leading to a bowl 33 located at the bottom of the machine. The trip lever 34 is preferably connected to the table by a link 35 universally pivoted to the side of the table. To prevent the movement of the trip lever, 50 by turning the entire machine out of the vertical, a suitable supporting dog 36 may be pivoted at any convenient point adjacent to the bottom of the coin chute and provided with a projection or tooth 37 extending under the end of the lever 34 to support the same in its normal position. A very light spring 38 bearing against the back of the free end of the dog, holds the latter in the position illustrated in Fig. 7, wherein the 55 lever is supported. The dog is formed with an inclined face 39 which the coin engages in its fall to free the lever, just before it hits the projecting end of the lever to actuate the same. The portion 39 of the dog may be in 60 the path of the coin while the rest of the dog

may be to one side as illustrated in Fig. 5. Thus the body of the dog is out of the way of the coin and does not interfere with the movement thereof in actuating the lever. The tilting table may be slightly weighted 70 so as to overcome the slight resistance offered by the dog against the return of the trip lever to normal position.

In Figs. 8, 9 and 10, illustrating a modified form of coin chute and trip lever, the 75 coin chute 40 is formed with a laterally extending mouth 41 into which extends, preferably through a slot 42, the rounded end 43 of the trip lever 44. After the coin strikes the end of the lever and starts to travel 80 toward the mouth of the chute, the curved wall 45 of the chute engages the edge of the coin and causes it to roll slightly to one side of the lever so that when the mouth of the chute is reached, the coin drops to one side 85 into the coin box. By this arrangement the coin is not required to move past the end of the lever to drop into the coin box and is merely required to roll to one side of the lever. 90

In the form illustrated in Fig. 11 for vending long cylindrical articles as stick candy or lead pencils and the like, the tilting table 50 is elongated laterally and the trip lever 51 is formed with an arm 52 so as to 95 engage the tilting table adjacent to the mid-width thereof. This may be accomplished by forming the end of the arm 52 with an upwardly extending portion 53 constituting the point of contact with the table. The 100 construction otherwise need not differ materially from the other forms illustrated.

In the further modified form illustrated in Fig. 12, wherein rectangular articles are dispensed, the tilting table 60, operated by the 105 tripping lever 61 is formed preferably with a plurality of rolls 62 which permit the rectangular object to readily slide down the table and discharge past the flap 63 into the bowl 64. 110

It will thus be seen that I have provided a mechanism which automatically discharges an article from a container by the impact of the coin itself without the aid of any further manual operation aside from the inserting of the coin in the slot. 115

Although I have shown the various forms of machine adapted to discharge the articles one at a time, it will be readily understood that it is merely a matter of varying the 120 proportion of the parts to obtain the discharge of two or more articles in case it is desired to sell more than one article for the coin.

Having thus described my invention, I 125 claim as new and desire to secure by Letters Patent:

1. In combination with a long comparatively narrow casing of a container having a discharge opening a tiltable member pivoted 130

adjacent the vertical center line of the lowermost article, said member comprising a guideway and an arm at an angle thereto, said arm extending from the pivot to a point 5 to one side of the center line of the lowermost article and contacting and supporting the same, and a lever fulcrumed transversely of the pivoted member and engaging said member for tilting the same, said lever 10 having a portion adapted to be struck by a moving object, said member returning to normal position to discharge the article deposited thereon and to support the succeeding article when the lever is freed from the 15 impulse of the actuating object.

2. In combination with a container having a discharge opening and a tiltable mem-

ber pivoted adjacent said opening comprising an arm adapted to support the lowermost article, a lever for tilting said member 20 having a portion of the same adapted to be hit by a moving object to actuate the same, and a spring dog engaging the lever to hold the same in normal position said dog being provided with an offset cam face which is 25 hit by the moving object to disengage the dog previous to its actuating the lever.

Signed at New York in the county of New York and State of New York this eleventh day of Sept. A. D. 1913.

ARTHUR D. LOVEREN.
